(57) **CLAIM**

The ornamental design for a bottle wrap, as shown and described.

DESCRIPTION

FIG. 1 is a front view of a bottle wrap showing the new design; FIG. 2 is a back view of the bottle wrap as shown in FIG. 1; FIG. 3 is a right side view of the bottle wrap as shown in FIG. 1;

FIG. 4 is a left side view of the bottle wrap as shown in FIG. 1;

FIG. 5 is a bottom view of the bottle wrap as shown in FIG. 1; and,

FIG. 6 is a top view of the bottle wrap as shown in FIG. 1. Features shown in dashed lines immediately adjacent the solid lines represent the bounds of the claim and all other dashed lines, including the dashed lines depicting the bottle, are for illustrative purposes only. None of the dashed lines form a part of the claimed design.
